Term of patent 14 years

(Cl. D14—6)

Fig. 1.

Fig. 2.

Fig. 3.

Fig. 4.

FIG. 1 is a front elevational view of a combined vehicle wind and insect deflector, showing my new design;

FIG. 2 is a top plan view of FIG. 1;

FIG. 3 is an enlarged end view of FIG. 1; and

FIG. 4 is a front perspective view of FIG. 1.

The characteristic features of my design reside in the triangular shaped plane in the center in combination with the angular bend directly below said plane.

I claim:

The ornamental design for a combined vehicle wind and insect deflector, as shown and described.
